(57) **CLAIM**

The ornamental design for a table transport apparatus as shown and described.

DESCRIPTION

FIG. 1 is a top-front-left perspective view of a table transport apparatus according to the claimed design.

FIG. 2 is a top-rear-left perspective view of the table transport apparatus.

FIG. 3 is a bottom-rear-right view of the table transport apparatus.

FIG. 4 is a rear view of the table transport apparatus.

FIG. 5 is a rear-left perspective view of the table transport apparatus.

FIG. 6 is a left side view of the table transport apparatus.

FIG. 7 is a front view of the table transport apparatus.

FIG. 8 is a right side view of the table transport apparatus.

FIG. 9 is a top view of the table transport apparatus.

FIG. 10 is a bottom view of the table transport apparatus.

FIG. 11 is a side sectional view of the table transport apparatus along line 11-11 in FIG. 9.

FIG. 12 is a perspective sectional view of the table transport apparatus along line 11-11 in FIG. 9.

FIG. 13 is a rear sectional view of the table transport apparatus along line 13-13 in FIG. 9; and,

FIG. 14 is a perspective view of the table transport apparatus in an example use environment including a table.

The dash-dash broken lines in the drawings depict portions of the table transport apparatus that form no part of the claimed design.

The broken line showing of the table in FIG. 14 depicts environment that form no part of the claimed design.

The dash-dot broken lines showing the sectional lines form no part of the claimed design.

The oblique line hatch shading in the drawings illustrates interior portions of the table transport apparatus.

1 Claim, 14 Drawing Sheets
